UNITED STATES PATENT OFFICE.

WILLIAM C. ANDERSON, OF TOLEDO, OHIO, ASSIGNOR TO THE W. L. LIBBY
& SON COMPANY, OF SAME PLACE.

DESIGN FOR THE ORNAMENTATION OF GLASS DISHES.

SPECIFICATION forming part of Design No. 21,364, dated March 8, 1892.

Application filed December 18, 1891. Serial No. 415,558. Term of patent 7 years.

To all whom it may concern:

Be it known that I, WILLIAM C. ANDERSON, a citizen of the United States, residing at Toledo, in the county of Lucas and State of Ohio, have invented a new and useful Design for the Ornamentation of Glass Dishes, of which the following is a full, clear, and exact description, such as will enable artisans in the trade to use the same in ornamenting dishes.

In the drawings forming a part of this specification, Figure 1 represents a plan view of a dish ornamented with my design, and Fig. 2 represents a cross-sectional view of the same.

The leading features of my design consist in the representation of a six-pointed star, as shown, crossing the major portion of the field ornamented, and rosettes arranged upon the outfield between the points of the star.

The minor features of my design will be pointed out in detail hereinafter.

Referring to the drawings, which are correct representations of my design, it will be noticed that the edges of the dish are scalloped; but this forms no part of my design and may be omitted, if desired.

A indicates a series of prismatic ribs or bosses extending across the field to be ornamented. Intersecting and meeting each other, as shown, producing a six-pointed star and a hexagonal-shaped central figure connecting the diametrically-opposite points of the star-shaped figure, is a series of similar ribs or bosses B, said ribs crossing each other at the center of the dish and dividing the hexagonal-shaped central figure into a number of similarly-shaped trapezoids, the surfaces of said trapezoids being chased, as shown at C.

D indicates a series of narrow prismatic ribs or bosses A, which produce at their intersections polyhedral angles d. Upon the

outfield of the surface ornamented are shown rosettes or bosses E, said rosettes being arranged between the points of the star, and are represented as composed of a central star-shaped figure F, formed of a plurality of centrally-intersecting prisms f, an annular ring G, surrounding said center F, and a plurality of pyramidal-shaped bosses H, arranged in concentric circle about said ring G, the pyramids in each outer circle increasing in length, 45 as clearly shown.

K represents a plurality of divergent prisms arranged upon opposite sides of the several points of the star-shaped figure, said prisms ornamenting the field between two adjacent 55 rosettes E.

From the above it will be seen that I provide a skeleton star-shaped figure, which is divided into a series of figures, ornamenting the outfields between the points by rosettes, 60 and also ornamenting the field between the rosettes.

Having thus described my design, what I claim is—

The design for the ornamentation of dishes, 65 as herein described and shown, consisting of a star-shaped figure crossing the field ornamented, said star-shaped figure being divided into a series of similar figures, rosettes arranged between the points of the star-shaped 70 figure, and prisms arranged at the points of the same between the said rosettes.

In testimony that I claim the foregoing as my own I hereby affix my signature in presence of two witnesses.

WILLIAM C. ANDERSON.
